US0D1012866S

(12) **United States Design Patent** (10) **Patent No.:** **US D1,012,866 S**
(45) **Date of Patent:** **** Jan. 30, 2024**

(54) **TEMPERATURE CONTROL DEVICE**

(71) Applicant: **ARIZE CORPORATION**, Anaheim, CA (US)

(72) Inventor: **Liang Wang**, Shenzhen (CN)

(**) Term: **15 Years**

(21) Appl. No.: **29/831,937**

(22) Filed: **Mar. 23, 2022**

(51) **LOC (14) Cl.** **10-04**

(52) **U.S. Cl.**

USPC **D10/50**; D13/162

(58) **Field of Classification Search**

USPC D13/162, 168; D14/155, 240, 358; D10/49, 50, 104.1, 106.1

(57) **CLAIM**

The ornamental design for a temperature control device, as shown and described.

DESCRIPTION

FIG. 1 is a perspective view of a temperature control device showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depict portions of the temperature control device that form no part of the claimed design.

1 Claim, 7 Drawing Sheets
